DRAFTING TABLE

Ingram V. Stovern, Sheboygan, Wis., assignor to
 Engineering Manufacturing Co., Sheboygan,
 Wis., a corporation of Wisconsin

Application June 12, 1948, Serial No. 32,573

6 Claims. (Cl. 311—36)

1

This invention relates to drafting tables and has special reference to a novel table leg and support construction particularly suited for drafting tables.

An object of the invention is the provision in a drafting table of table top supporting means comprising at least one suitable rod member on a support, formed by interlocking parts, and novel clamping means for simultaneously securing the interlocking parts of the support and the rod member in a rigid adjusted relation.

Another object of the invention is the provision of a drafting table of the above character having novel clamping means for securing the parts together as described that is readily accessible whereby the position of the table top may be readily adjusted to a desired position.

Another object of the invention is the provision in a drafting table of the above character of novel clamping means for securing the parts together as described that permits of easy assembly and disassembly of the component parts of the drafting table without special fitting of the parts.

Another object of the invention is the provision in a drafting table of the above character of novel supporting means for securing the parts together as described that is rugged, that is positive in its action and that is relatively inexpensive to manufacture.

Other objects and advantages of the invention will become apparent from the following detailed description taken in connection with the accompanying drawings, in which—

Figure 1 is a perspective view of a drafting table embodying the present invention;

Fig. 2 is an enlarged fragmentary view showing the components of the drafting table in tightly assembled relation;

Fig. 3 is an end view of Fig. 2, and

Fig. 4 is a sectional view taken substantially on the line 4—4 of Fig. 3.

Referring now to the drawings, the invention is shown embodied in a drafting table. In general, the table comprises a suitable top 11 having a flat upper surface and mounted on a support 12 as by spaced tubular or rod members 13 connected along one edge of the table top and spaced adjustable telescoping members 14 connected along the opposite edge of the table top. The tubular members 13 are connected to the support 12 in a manner to be presently described and then extend upwardly from the support and as shown herein curve outwardly to be pivotally connected to one end of braces 16 extending

2

transversely of the underside of the table top 11 and secured thereto in a conventional manner. It is to be understood that tubular members 13 may be straight or curved as shown depending on the relative pivotal connection desired. At one end, the telescoping members 14 are pivotally attached to the support 12, in spaced relation to the connection between the support and the tubular members 13, and the opposite ends of the telescoping members are connected (not shown) to the opposite end of the braces 16. Thumb screws 17 secure the telescoping members 14 in a desired adjusted position.

In general, the support 12 comprises spaced base members 18 and a spreader 19 disposed between and supported by the base members 18. Since the base members 18 are of similar construction, only one of them will be described in detail hereinafter. As shown, the base member 18 is formed by inclined legs 21 and 22. At their lower ends the legs are shaped to rest on the floor or the like, and at their upper ends the legs are in spaced relation and interconnected by a plate 23 secured to the outwardly facing side of the legs as by screws as shown in Figures 1 and 3. The upper ends of the legs are pre-shaped and are in spaced parallel relation, the spacing between the legs being slightly greater than the width of the spreader 19 so that the legs 21 and 22 together with the interconnecting plate 23 form a pocket or slot 24 for the end of the spreader 19. A strip 26 secured to each leg 21 and 22, as by screws, and disposed on the inwardly facing side of the base member 18 provides a guide for the spreader 19 for positioning the parts during assembly and a rest for the spreader after the parts are assembled. The strip 26 also serves to reinforce and stiffen the sub-assembly of the legs 21 and 22 and the plate 23.

The spreader 19 is shown herein as being formed by a metal tubular member having a generally elongated rectangular cross-section. Extending axially of each end of the spreader is a projection 27 in the form of a U-shaped strap. The legs 28 and 29 of the U-shaped strap 27 are secured, as by welding or the like, to the sides 31 and 32, respectively, of the spreader 19 as best seen in Fig. 4 and an intermediate bridging portion 33 extends outwardly from the ends of the spreader. The bridging portion 33 at each end of the spreader in the assembled position of the parts extends through an aperture 34 in each plate 23 and projects beyond the respective plates a sufficient distance so that the tubular members 13 supporting the table top 11 are embraced by

the bridging portions 33 of the respective U-shaped straps 27.

As best seen in Fig. 2, the upper and lower edges 36 and 37, respectively, of the plates 23 are inclined at angles with respect to the plane of each plate 23 and are formed with notches or saddles 38 and 39, respectively, spaced relatively far apart and shaped to receive the respective tubular members 13 at each end of the support. These notches are disposed on opposite sides of each U-shaped strap 27 and are in alignment therewith as seen in Fig. 3. A single hand screw 41 threaded through each bridging portion 33, which may be reinforced by a member 42 secured thereto as by welding, is mounted to have its end abut against the respective tubular member 13. The screws 41 may be adjusted from a loosened position in which the tubular members 13 may be moved relative to the support 12 to adjust the height of the table top 11, or they may be tightened to a position in which the screws 41 engage the tubular members 13 and force the latter into tight engagement with the saddles 38 and 39 to positively secure the tubular members 13 in a fixed relation with the spreader 19 and the respective base members 18.

The above construction has many advantages both from an assembly standpoint and from a use standpoint. From the foregoing description it is apparent that this construction may be assembled in a minimum of time. To assemble the support 12 it is only necessary to place a base member 18 at each end of the spreader 19 so that the end of the spreader 19 is received in the groove 24 in each base member 18 and the U-shaped strap 27 projects through the aperture 34 in each plate 23. Thereafter, assuming that the tubular members 13 have been secured to the table top 11 as described, it is only necessary to pass the ends of the tubular members 13 through the bridging portions 33 so that the latter embrace the respective tubular members 13. The hand screws 41 may then be tightened to secure the parts in position. The height of the table top 11 may then be adjusted by loosening the hand screws 41 so as to move the tubular members 13 relative to the support 12 until the table top 11 is at the desired height. After the table top 11 has been positioned as desired, the hand screw 41 at each end of the support 12 is positively tightened. This construction also may be readily disassembled. This is an important feature since frequently it is desirable to dismantle tables and store them for later use. Thus, to disassemble the table, assuming that the rods 14 have been disconnected, it is only necessary to unscrew the hand screws 41 from the bridging portions 33. The tubular members 13 may then be withdrawn from the bridging portions 33 and the bases 18 removed from the spreader 19. Since only two hand screws 41 have to be removed a minimum of time is required to effect the disassembly of the table. The shape of the components also permits them to be readily stored in a minimum of space.

As can best be seen in Fig. 2, when the hand screws 41 are tightened, the latter engage the tubular members 13 at a point intermediate the saddles 38 and 39. This arrangement is such that a force is applied intermediate the saddles which tends to urge the portion of the tubular member 13 between the saddles toward each plate 23. The rigid edges of the plates defining the saddles 38 and 39 oppose this force and consequently each tubular member is securely held in

place by the forces acting between the saddles on one side of each tubular member 13 and the adjustment screws 41 engaging the opposite side of each tubular member 13. Since the U-shaped member 27 is connected to the spreader 19 which abuts against one side of the plate 23 and the hand screws 41 engage the tubular members 13 on the opposite side of the plate, forces are also set up when the hand screws are tightened, that cause the spreader 19, the plate 23 and the tubular members to be urged together in a tight fixed relation. Spacing the saddles 38 and 39 relatively far apart and disposing the hand screws 41 so that they engage the tubular members 13 at a position in between the saddles, as shown, assures that the upper ends of the tubular members are prevented from moving laterally or twisting. As a result the table top is rigidly supported.

From the above description and operation of applicant's construction it is seen that adjustments may be effected in a very simple manner, since a single hand screw 41 at each end of the support when in a loosened position permits the table top 11 to be adjusted to any desired height and when in a tightened position positively insures that the spreader 19, the base members 18 and the tubular members 13 are in a fixed position so that the table is rigid.

I claim:

1. In combination, a spreader supported at one end and having a projection at its opposite end with an aperture extending therethrough, a base having a groove for receiving and supporting said opposite end of the spreader and an opening for receiving said projection, said base and said spreader interfitting to position the aperture in the projection on the side of the base away from the groove, spaced members mounted on the side of the base away from the groove, said members having notches arranged to be in alignment with said aperture in the projection, a rod for supporting a member in spaced relation to said spreader extending through said aperture in the projection and engageable with said spaced members, and adjustable abutment means intermediate said members mounted on said projection and engageable with said rod on the side thereof away from said spaced members to urge the rod into said notches into engagement with the spaced members and to force the base into tight assembled relation with the spreader.

2. In a table having a top, means for supporting the top comprising spaced rods arranged to be attached to the top, spaced base members each including a pair of legs, said legs having their lower ends shaped to rest on the floor and their upper ends in spaced relation, a plate having an aperture and disposed at one side of the upper ends of the legs for securing them together, the spacing between the legs defining with the associated plate a groove in each base member in communication with the aperture in the plate and facing the other base member, flanges on the upper and lower edges of each plate spaced relatively far apart and inclined at an angle to the plane of the plate, said flanges having notches on their outer edge on opposite sides of said apertures and shaped to receive one of said rods, a spreader supported by said base members and having its ends received in the grooves thereof, a projection at each end of the spreader shaped to extend through the aperture in the associated plate, each projection having an opening in alignment with the notches in the associated

flanges and shaped to receive one of said rods, and a single hand screw mounted on each projection to be engageable with the corresponding rod on the side thereof away from that engaged by said flanges, said screws being movable between a position in which the rods are free to move relative to the plates to adjust the position of the table top and a position in which the base members, the spreader and the rods are simultaneously clamped in a fixed relation.

3. In a table having a top, means for supporting the top comprising spaced rods attached to the top, spaced base members each comprising inclined legs, said legs having one end shaped to rest on the floor and their opposite ends positioned to be in spaced relation, a plate disposed at one side of the opposite ends of the legs for securing them together and having an aperture, the spacing between the legs defining with said plate a groove in each base member in communication with the aperture in the associated plate and facing the other base member, a spreader supported by said base members and having its ends received in said grooves, a projection at each end of the spreader extending through the aperture in the associated plate and having an opening therein for receiving one of said rods, spaced saddles positioned to be in alignment with the opening in the projection and shaped to engage the side of one of said rods, and a single manually manipulable adjustable abutment mounted on each projection to be engageable with the corresponding rod on the side thereof away from the saddles, each abutment being movable between a position in which the rod is free to move relative to the associated plate to adjust the position of the table top and a position in which the legs and interconnecting plate, the spreader and the rod associated with the abutment are simultaneously clamped in fixed relation.

4. In a table having a top, means for supporting the top comprising spaced rods arranged to be attached to the table top, spaced base members each having a groove facing the other base member and each having an aperture in communication with the associated groove, a spreader supported by said base members and having its ends received in said grooves, a projection at each end of the spreader extending through the aperture in the associated base member and having an opening therein for receiving one of said rods, spaced saddles on opposite sides of said aperture positioned to be in alignment with the opening in the projection and shaped to receive one of said rods, and a single adjustable abutment mounted on each projection to be engageable with the corresponding rod on the side thereof away from the spaced saddles, each abutment being movable between a position in which the rod with which it is associated is free to move relative to the associated base member to adjust the position of the table top and a position in which the associated rod is urged into tight engagement with the saddles, the associated base member, the spreader and the associated rod to simultaneously clamp the associated rod and base member and spreader in tightly assembled relation.

5. In a table having a top, means for supporting the top comprising spaced rods for attachment to the table top, a spreader, U-shaped straps extending axially of each end of the spreader comprising spaced legs and a bridging portion interconnecting said legs, said legs being

positioned at each end of the spreader to receive one of said spaced rods therebetween, a base member at each end of the spreader having a groove for receiving the end of the spreader, 5 each base member having an aperture for receiving the strap at the end of the spreader, spaced saddles on each base member on the side thereof away from the groove, said saddles being disposed on opposite sides of the aperture and 10 arranged to be in alignment with the opening between the legs of the U-shaped members, said saddles being positioned to engage the rods on the side thereof away from said bridging portion, and an adjustable abutment mounted on each 15 strap to engage the respective rod embraced thereby on the side thereof away from the saddles, each abutment being movable from a position in which the associated rod is free to move relative to the associated base member to adjust 20 the position of the table top and a position in which the associated base member, the spreader and the associated rod are simultaneously clamped in a fixed relation.

6. In a table, the combination of a table top 25 having a forward and a rearward edge, spaced base members disposed below said top and between said edges, each of said base members having a groove facing the other base member and each having an aperture in communication with 30 the associated groove, a spreader supported by said base members and having its ends received in said grooves, a projection at each end of the spreader extending through the aperture in the associated base member and having an opening 35 therein, spaced saddles on opposite sides of each aperture positioned to be in alignment with the opening in the projection, spaced rods having their lower ends shaped to extend through the openings and to be engaged by said saddles and 40 their upper ends deformed to be adjacent the forward edge of the table top, means for effecting a pivotal connection between the rods and the table top adjacent the forward edge, a single adjustable abutment mounted on each projection to be 45 engageable with the associated rod on the side thereof away from the spaced saddles to secure the base member, the spreader and the rod in a tightly assembled relation to maintain a pre-selected elevation of the forward edge of the table 50 top, and an adjustable member connected between each base member and the table top adjacent the rearward edge for adjusting the elevation of the rear edge of the table independently of the forward edge while the latter is at a pre-selected elevation.
